UNITED STATES PATENT OFFICE

2,021,220

DRIVING MECHANISM

Milton H. Ballard and Donald G. McLean, Beverly, Mass., assignors to United Shoe Machinery Corporation, Paterson, N. J., a corporation of New Jersey

Original application June 29, 1931, Serial No. 547,546. Divided and this application December 3, 1934, Serial No. 755,685

4 Claims. (Cl. 74—405)

This invention relates to driving mechanism and is herein illustrated as embodied in a press of the type commonly known as a clicking machine such as that illustrated in United States Letters Patent No. 921,503, granted May 11, 1909, upon an application filed in the name of Arthur Bates and comprising a work supporting bed, a reciprocating post and a presser arm extending laterally from the post and movable therefrom over the bed and toward and away therefrom for exerting pressure applying operations positioned upon work supported by the bed to produce blanks. This application is a division of application Serial No. 547,546, filed June 29, 1931 in our names.

It is an object of the present invention to provide an improved machine of the type referred to which, without sacrificing any of the characteristic advantages of such machines as heretofore built, will be so constructed as to facilitate the removal of certain parts for adjustment and servicing.

To this end and as illustrated, the machine is provided with a flywheel carried by a shaft for reciprocating the presser member and which is driven by a motor mounted upon the frame of the machine for movement relatively to the flywheel in such manner that the motor and flywheel can readily be disconnected when it is necessary to remove the flywheel. Preferably, and as shown, the motor is carried by a bracket pivotally mounted upon the frame, and means is provided for releasably securing the bracket in position with the motor operatively connected to the flywheel.

The invention is disclosed in the following detailed description and in the accompanying drawings and will be pointed out in the claims.

In the drawings, Fig. 1 is a front elevation of a machine illustrating one embodiment of our invention;

Fig. 2 is a side elevation of a portion of the machine illustrating the motor driven mechanism;

Fig. 3 is a detailed view partly in section of a motor bracket locking device; and

Fig. 4 is an end view partly in section of a portion of the locking device.

As illustrated in Figs. 1 and 2 of the drawings, the machine comprises a C-shaped frame 10 upon one side of which is slidably mounted a hollow upright post 12 to which is secured a presser member or arm 14 arranged for cooperation with a cutting block 16 mounted upon the opposite side of the frame, to operate on work,

such as leather or other sheet material, positioned upon the bed. As is customary in machines of this type, the post 12 is movable angularly about its axis so that the presser arm 14 secured thereto can be moved over the bed 16 about the axis of the post, for example into operative position relatively to a freely movable cutting die located upon the work. The post is arranged to be reciprocated vertically by a connecting rod 18 operatively connected to an eccentric 21 upon a rotary shaft 20 which is controlled by a one-revolution clutch, not shown, for causing rotation of the shaft 20 by a flywheel 22 driven by a motor 24 supported on the frame.

Preferably, and as shown in Figs. 1 and 2, the motor 24 is supported on a bracket 26 depending from a shaft 28 pivoted in ears 30 on the frame 10. The flywheel 22 is provided with a circular rack 32 which is arranged to engage a pinion 34 on the motor. The flywheel also has flanges 36 which act as guards to prevent injury to the teeth of the rack 32. These flanges would operate to prevent withdrawal of the flywheel unless the pinion and flywheel were relatively movable radially of the flywheel. However, the pivotal mounting of motor bracket 26 makes it possible to move the pinion 34 out of the line of movement of the flanges when it is necessary to remove the flywheel from the shaft 20. In order to lock the motor bracket in position with the pinion 34 in mesh with the rack 32, the motor bracket 26 is provided with a depending portion 38 having a slot 40 within which is positioned a retaining bar 42 (Figs. 1, 2, 3 and 4). The bar 42 is arranged for pivotal movement about a shaft 43, Fig. 1, and carries a spring 44 bearing against washers 45 in engagement with a pin 46 on the bar and a boss 47 on the motor bracket, the spring being normally operative to force the motor bracket outwardly. The end of the bar 42 is provided with an elongated slot 48 within which is located a retaining pin 50 and which is supported in the portion 38 of the motor bracket. At one end of the slot 48 the bar 42 is provided with a tapered recess 52 adapted to receive a correspondingly tapered portion 54 of the pin 50. The tapered portion 54 terminates in a shoulder 56 which, when the bracket 26 is swung outwardly from the frame of the machine, 50 rides upon the outer side of the bar 42, the shoulder being forced into engagement with the bar by a spring 58 which surrounds a reduced end portion 60 of the pin 50. When it is desired to place the pinion 34 and the rack 32 in mesh, 55

the motor bracket is pushed inwardly and the pin 50 slides along the slot 48 until the spring 58 forces the tapered portion 54 into the recess 52 of the bar, thus locking the bracket in position. The bracket is released by pulling the pin 50 outwardly by means of a handle 62 thus removing the tapered portion 54 from the recess 52, and permitting the spring 46 to force the bracket outwardly. This construction provides 10 a convenient means whereby the removal of the flywheel is facilitated.

Having described the invention, what we claim as new and desire to secure by Letters Patent of the United States is:

- 15 1. A machine having a frame, a shaft mounted in the frame, a flywheel on the shaft, a bracket mounted upon the frame for movement toward or away from the flywheel, a motor secured to the bracket and having a pinion adapted to engage the flywheel for driving the same, means tending to force the bracket outwardly from the flywheel, a link pivoted upon the frame and extending into engagement with the bracket and manually-controlled means on the bracket for engaging the link to lock the bracket in position with the pinion in engagement with the flywheel.
- 20 2. A machine having a frame, a rotary shaft, a flywheel carried by the shaft, an electric motor for driving the flywheel, a bracket pivotally mounted upon the frame and secured to the motor for supporting it, a member secured to the frame and extending loosely through the bracket, a spring on said member operable normally to force the bracket and motor outwardly from the frame, and manually operable means mounted upon the bracket and arranged to engage said member for securing the bracket to

said member in predetermined position relatively to the frame.

3. A machine having a frame, a rotary shaft, a flywheel carried by the shaft and having a toothed rack, an electric motor having a driving pinion adapted to mesh with the rack for driving the flywheel, means for supporting the motor comprising a bracket pivotally mounted upon the frame, a spring normally operative to force the bracket outwardly of the frame to release the pinion from the rack, and cooperating means carried by the bracket and the frame operable upon movement of the bracket inwardly to secure the bracket in position with the pinion and rack in mesh.

4. A machine having a rotary shaft, a flywheel carried by the shaft and having a circular rack, an electric motor having a driving pinion adapted to mesh with the rack for causing rotation of the flywheel, means for supporting the motor 20 comprising a bracket pivotally mounted upon the frame, a spring normally operative to force the bracket and motor angularly of the frame into position in which the pinion and rack are disconnected, a link pivotally mounted upon the 25 frame and extending through the bracket, a retaining pin mounted in the bracket extending through an elongated slot in the link, a tapered shoulder upon the pin adapted to engage a corresponding recess in the link upon movement of the bracket toward the frame, and means for forcing the shoulder into the recess whereby the bracket is locked in position with the pinion in mesh with the rack.
